CONNECTOR-YOKE ASSEMBLY FOR ELECTRICAL CABLES AND THE LIKE
Malcolm Bethea, Jr., P.O. Box 1407, Birmingham, Ala.
Filed May 7, 1964, Ser. No. 365,704
3 Claims. (Cl. 287—100)

This invention relates to an improved connector for removably joining yoke plates and insulator strings used in suspending power lines and the like, and to an improved assembly embodying the same.

In this art it often is necessary to change out insulator strings, or repair the same without deenergizing the lines. It is desirable, therefore, that the connector and yoke supporting the lines, especially if the lines are hot, be held rigidly in position during the assembly of the "ball" of the insulator string into the socket of the connector. At the same time, once assembled, it is desirable that there exist limited pivotal movement between the connector and the yoke in the plane of the yoke. So far as I am aware prior devices of this type comprise simply a vertically fixed, pivotal connection between the connector and bundle yoke. Consequently, when the yoke is raised vertically, thereby to move the ball on the end of the insulator string to the bottom of the socket for lateral sliding from the socket, undesirable pivotal movement between the yoke and connector is permitted. Remembering that such work is carried on by workmen high above ground, often with the lines energized, thus requiring the use of hot sticks, the jockeying of the ball from and into such a pivotally arranged connector-yoke is difficult and dangerous.

My invention has for its prime object to provide a connector-yoke assembly in which, when the yoke is raised, the connector is temporarily rigidly and non-pivotally engaged with the yoke, or stabilized, whereby the enlarged end of the insulator string may easily be removed from or inserted into the socket.

Another object is to provide a connector in the form of a clevis, the bifurcated legs of which straddle the yoke and the upper end of which carries the socket for receiving the ball of the insulator string, there being aligned vertically elongated slots through the legs of the clevis through which slots and through the yoke passes a securing pin, all so dimensioned and arranged that when the pin is near the top of the slots, the top of an adjacent part of the yoke contacts the base of the clevis, thus holding the connector and yoke against relative pivotal movement.

Apparatus illustrating features of my invention is shown in the accompanying drawing, forming a part of this application, in which:

FIG. 1 is a fragmental detail sectional view taken generally along line 1—1 of FIG. 2 and showing the parts in the position which they occupy when in normal use;

FIG. 2 is a detail sectional view taken generally along line 2—2 of FIG. 1;

FIG. 3 is a view corresponding to FIG. 1 and showing the position occupied by the parts when the yoke has been raised upwardly, preparatory to removing the ball of the insulator string from the socket; and,

FIG. 4 is a detail sectional view taken generally along line 4—4 of FIG. 3.

Referring now to the drawings for a better understanding of my invention I illustrate the same in association with an insulator string indicated generally by the letter S and a bundle yoke for supporting electrical conductors indicated generally by the letter Y.

As is understood, the insulator string S embodies a plurality of insulators 10, there being a rod 11 extending

2

from the center of the individual insulators. At the lower end of the rod is a ball or enlargement indicated at 12.

The yoke Y comprises the arms 13 and a central, flat portion 14 which may be described as being generally of plate configuration. As will be understood, the conductors are supported from the ends of the arms 13, in a fashion well known and hence not shown in the drawings. Further, the yoke may be of the solid plate-type, or it may be open in which case other arms 16 may be formed integrally with extensions of other arms, not shown, thus forming a closed geometrical figure.

My improved connector indicated generally by the numeral C embodies essentially two parts. First, there is an upper part 17 having therein the socket portion 18 which receives the ball 12. As is understood, the socket portion is open at one side as at 19 whereby when the parts are in the position of FIGS. 3 and 4 the parts may be moved relatively laterally to each other, whereby the pin 11 may pass through the slot, the ball passing through the wider, bottom portion thereof. It will be understood that a cotter pin or like member 21 is inserted beneath the ball 12 when the parts are assembled, thus to prevent accidental displacement.

Next, it will be seen that in side view the connector is generally in the form of a clevis having depending legs 22 joined to the upper portion 17. The legs 22 are disposed to straddle the upper or plate-like portion of the yoke Y as illustrated in FIGS. 2 and 4. In the legs 22 I provide vertically elongated, horizontally aligned slots 23. A hole 24 is provided in the plate-like portion 14 thereby to receive a pin 26 which may be secured in place by a cotter pin 27.

From what has been described the construction and function and advantages of my improved assembly may now be more fully explained and understood. With the parts in the position of FIGS. 1 and 2 it will be seen that the yoke may pivot about the pin relative to the connector only as limited by the clearance existing between a pair of shoulders 28 on the enlarged, upper surfaces of the arms 13, indicated at 13a. In this position, which is the normal or suspended position of the parts, the assembly acts in the ordinary manner to give a certain amount of freedom of movement between the parts. When it is desired to remove the ball 11 of the insulator string from the socket the conductor yoke is engaged by a hot stick, if the lines are energized, and the same is pushed upwardly. This action causes the top 14 of the yoke Y to move upwardly, the slotted openings 23 permitting this. This motion continues upwardly until such time as the top 14a of the yoke engages the base 29 of the connector C, at the top of the legs 22 thereof. Continued upward movement moves the yoke and connector upwardly to a position where the ball 12 engages the bottom of the socket, it being understood that the cotter pin 21 will have been removed to permit this action. With continued upward pressure being applied to the yoke through the hot stick it will be seen that due to the engagement of the surfaces 14a and 29, no relative pivotal movement is permitted between the connector C and the yoke. Therefore, the workman may now push upwardly and laterally with the hot stick still engaged in the yoke, whereby the ball 12 slides freely through the slide slot 19 provided alongside of the socket 18.

When it is desired to reassemble the parts the yoke is simply engaged with the hot stick, in which position the connector C will automatically slide to a position shown in FIGS. 3 and 4, the assembly is raised, and slid laterally relative to the ball in proper position for easy engagement.

From the foregoing it will be apparent that I have devised an improved connector-yoke assembly. As stated,

the principal advantage of my invention is the fact that it facilitates the assembly and disassembly of the parts, particularly when the lines are energized. It will readily be apparent that the parts are extremely simple and are without complexities either as to manufacture or use. By means of my invention I have greatly reduced the hazards occasioned by workmen having to jockey or realign parts when attempting to place the ball 12 in the socket 18, or to remove the same.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. In a connector-yoke assembly:

- (a) a connector body having a depending portion lying alongside a generally vertically extending portion of the yoke,
- (b) there being a vertically elongated slot through said depending portion of the body,
- (c) a pin passing freely through said slot so as to be slidable therein and through an aperture in said yoke so as to be movable with the yoke,
- (d) an abutment carried by said body above said slot,
- (e) a stop member carried by the upper end of said vertically extending portion of the yoke and aligned with said abutment so as to engage said abutment when the yoke is moved to its farthest uppermost position relative to said body and prevent relative rotation between the yoke and said body and in position to disengage said abutment upon downward movement of said yoke relative to said body, and

(f) means adjacent the upper end of said connector for connecting said connector to a superjacent member.

2. In a connector-yoke assembly as defined in claim 1 in which the depending portion of the connector body comprises a pair of vertical legs spaced apart, and slidably receiving said vertically extending portion of the yoke to permit the yoke and connector to partake of relative limited vertical sliding movement and said abutment is defined by the base portion of said body joining said legs.

3. In a connector-yoke assembly as defined in claim 1 in which the yoke is provided with other stop members adjacent either side of said vertically extending portion of the yoke which contact said body and limit pivotal movement of said body relative to said yoke beyond a predetermined amount when the yoke is suspended from the connector by said pin.
